UNITED STATES PATENT OFFICE.

DANIEL MILLS, OF PHILADELPHIA, PENNSYLVANIA, ASSIGNOR TO STANDARD SEWING MACHINE COMPANY, OF CLEVELAND, OHIO, A CORPORATION OF OHIO.

THREAD-CUTTING MECHANISM FOR SEWING-MACHINES.

1,016,226

Specification of Letters Patent.

Patented Jan. 30, 1912.

Application filed May 23, 1902. Serial No. 108,667.

To all whom it may concern:

Be it known that I, DANIEL MILLS, a citizen of the United States, residing at Philadelphia, Pennsylvania, have invented new and useful Improvements in Thread-Cutting Mechanism for Sewing-Machines, of which the following is a specification.

This invention relates to improvements in sewing machines, and especially to that class of sewing machines in which the mechanism is automatically stopped after making a desired predetermined number of stitches, as for example, in button-sewing, buttonhole-stitching and bar-tacking machines, in all of which the desired number of stitches are sewed at one point in the work, as at a button or buttonhole, and the machine then stopped and the work shifted before restarting the machine. In machines operating in this manner, as for example, in a button-sewing machine, which is the type of machine shown in the drawings of this application to illustrate my invention, a button is sewed to the fabric, the machine stopped, and the work then drawn through the machine to locate the fabric at another point at which another button may be sewed to the same. In such machines as heretofore constructed the needle and the bobbin threads are usually both pulled or drawn along with the fabric as the latter is shifted, and there is consequently much waste of thread thereby caused, as the thread is continuous, spanning the space from button to button, and is usually cut by the operator after the sewing on of the buttons is completed. This cutting operation of course causes a considerable loss of time in addition to the waste of thread.

The principal object of my invention is to avoid the waste of thread and loss of time incident to the use of this type of sewing machine, and I accomplish this by cutting the needle and bobbin threads after the sewing mechanism has made the desired number of stitches at a given point and has been automatically stopped, this cutting of the threads being performed by a suitable thread-cutter brought into action before the work is shifted to a new position, and preferably taking place simultaneously with the operation of the parts in releasing the work by its holder or presser. Before this cutting

operation takes place it is necessary that a sufficient length or quantity of thread be pulled from the needle and bobbin thread supplies to allow for the proper formation of the first stitch when the machine is re-started, and to do this, I provide means for operating to this end which are preferably automatically brought into action only during the formation of the last stitch of a determined number, such means, in the case of the needle thread, operating to receive and detain the last loop cast off by the looper in a manner whereby the usual take-up will be caused to draw from the needle thread supply the additional length or quantity required. Owing to the variation in the normal mode of pulling off and taking up the thread, which results from the pulling off of the extra quantity of needle thread during the formation of the last stitch to leave a cut end of considerable length, I also provide, in connection with means for normally tensioning said thread in the ordinary manner, means for releasing the tension at the proper point when this extra length of the needle thread is being pulled off, the parts being so organized as to cause the needle thread to be put under tension again just before the stopping of the machine, in order that the thread may be located with precision, held taut, and cut readily.

Another important object of the invention is to provide for the positive and automatic interlocking of the needle and bobbin threads as soon as the machine is re-started, and I accomplish this, and prevent loss of time, which would result if the operator were obliged to locate and grasp the cut end of the needle thread, by providing an automatic gripping device which will engage and hold the loose end of the needle thread loop so as to insure its positive interlocking with the bobbin thread and form a stitch immediately after the machine has re-started.

Other objects and advantages of the invention not hereinbefore referred to, but which will be hereinafter described, are illustrated in the accompanying drawings, in which—

Figure 1 is a front elevation, partly in section, of a "Standard" button-sewing machine having my invention applied

thereto. Fig. 2 is a rear view of the same, with parts broken away to illustrate the construction more clearly. Fig. 3 is a plan of the same. Fig. 4 is an under side view 5 of the same, with a part of the switch-cam broken away. Fig. 5 is an end elevation of the machine viewed from the left in Fig. 1. Fig. 6 is a vertical section of the same, the section being taken substantially on the line 10 6—6, Fig. 1. Fig. 7 is an enlarged plan of the bed-plate and certain adjacent parts showing the button-holding and other devices. Fig. 8 is an enlarged sectional front 15 elevation illustrating the operation of the various parts of the stitch-forming mechanism and a thread-gripper coöoperative therewith. Figs. 9 and 10 are enlarged sectional end elevations of the stitch-forming devices and of a loop-detainer and spreader co- 20 operative therewith, showing the respective positions of said detainer and spreader when it is out of action and when in its operative position. Figs. 11 and 12 are enlarged sectional plans illustrating the bobbin-thread 25 pull-off and the cutting device at different points in their paths of action. Figs. 13 and 14 are perspective views illustrating the manner in which the bobbin-thread is pulled off and both threads placed in cutting 30 position while the needle thread loop is spread by the combined thread detainer and spreader. Figs. 15 and 16 are perspective views illustrating different positions of a 35 thread-gripper for gripping and holding the cut end of the needle thread. Fig. 17 is an enlarged sectional detail through line 17—17 of Fig. 14, illustrating the positions of the bobbin-thread pull-off and cutter at the time the cutting operation takes place. 40 Similar characters designate like parts in all the figures of the drawings.

In said drawings, I have illustrated one type of sewing machine, in which the stitch-forming mechanism is adapted to be automatically stopped after making a determined number of stitches, the machine shown being a button-sewing machine of the well-known "Standard" sewing machine type, although my invention is equally applicable to other sewing machines for other purposes than sewing on buttons. Many of the parts of the machine illustrated are of well-known construction and are for convenience of illustration substantially as found in said "Standard" sewing machine, some of said parts being a bed-plate 1, an overhanging arm 2, an upper driving shaft 3 supported in bearings in said arm 2, a vertically-reciprocating needle-bar 4 operated from the driving shaft 3, a rotary shuttle or looper 5, a shuttle-driving shaft 6 supported in suitable bearings on the under side of the bed-plate and operated from the upper shaft 3 by 60 suitable connections, a take-up device 7, 65

operated in the usual manner from the upper shaft 3, a presser-bar 8 operating in the usual manner, a button-holder carried by said presser-bar, and suitable mechanism for shifting said button-holder for presenting the holes in the button to the needle in the proper manner, together with automatic stop mechanism for stopping the stitch-forming mechanism and other working parts at the end of a determined number of 70 75 stitches, various minor devices being also shown, to which special reference need not be made.

The button-holder carried by the presser-bar may be of any suitable construction, and is preferably detachably clamped to the presser-bar between a pair of nuts 10—10, said button-holder having the usual button-gripping jaws 13—13, between which a button 6 may be firmly held.

The button-holder may be vibrated back and forth to present first one and then another of a pair of holes in the button in a position to be entered by the needle in the following manner. The presser-bar, to 80 which the button-holder is secured, is pivotally mounted at its end in the arm of the machine and is vibrated back and forth in a direction transverse to the bed-plate by the usual operating connections employed 85 in this machine, and as said presser-bar is vibrated, the button-holder, and the button carried thereby, are also moved back and forth to present a pair of holes in the button to the needle alternately. The button-holder 90 is also pivoted to swing relatively to the presser-bar about the pivot 12 for the purpose of presenting the second pair of holes in the button in position to be entered by the needle. This swinging movement may 95 be communicated to the button-holder by a connecting-rod 28 adjustably secured to the rocker-arm or lever-arm 27 attached to the upper end of a short vertical shaft 25 extending through the bed-plate and working 100 in bearings at opposite sides thereof, and is derived from a rotary switch-cam 24 through another arm 29, which latter is secured to the lower end of the shaft 25 and provided with a pin which works in the 105 groove 24^a, see dotted lines, Fig. 3, of said cam and causes the shifting of the connecting-rod 28 and the button-holder at the proper time. This cam is geared directly 110 to the shaft 6 and driven therefrom by 115 worm gearing.

Any suitable automatic stop-mechanism may be employed for stopping the machine after making a predetermined number of stitches, a desirable form being that shown 120 and described in my prior Patent No. 635,267, dated October 17, 1899. In the present case, as in said patent, the shaft 3 has the usual hand-wheel or pulley 34 fast thereon and a driving or loose pulley 35 125 130

adapted to be clutched to, and unclutched from, said fast pulley 34. For the purpose of coupling these pulleys an elbow-lever 36 is pivoted on a bracket-arm 37, and one 5 end of this elbow-lever extends into an opening in a vertically operating slide-bar 39 and is adapted to be actuated thereby. The other or outer end of said elbow-lever extends into position to actuate a sliding 10 pin 40 controlling the clutch movement of the pulley 35. At its lower end the said slide-bar 39 is connected by a link 42 to a lever 43, one end of which latter is pivoted on a lug 44, while the opposite end of said 15 lever is bifurcated and embraces a pin projecting from a rock-arm 45 carried by a rock-shaft 46 suitably supported below the bed-plate, said rock-shaft having near its forward end another arm 48, preferably a cam 20 arm, for controlling the operation of a loop detainer and spreader hereinafter to be described. This shaft 46 is rocked in the proper direction whenever it is desired to couple the pulleys 34 and 35, and when 25 the pulleys are clutched together the elbow-lever 36 and the slide-bar 39 are held in position to effect such clutching by a suitable latch, such as the horizontally acting spring-pressed slide-latch 49, engaging with 30 the said slide-bar. By withdrawing the slide-latch 49 from engagement with the slide-bar 39 the latter will be automatically elevated and the other parts returned to a position to release the loose pulley 35 from 35 the fast pulley 34, a spring 54 being employed to effect this return movement. The fast pulley has two stop-rings 57 and 58 40 yieldingly connected therewith, in a manner as fully disclosed in my said prior patent. These stop rings are each provided with a projecting lip or stop-face, one of which, that on the ring 58, being adapted to strike the upper end of the slide-bar 39 when the latter is released by the slide- 45 latch and forced upward by the spring 54, so as to stop rotation of the pulley in one direction, while the ring 57 may have a slight over rotation due to the momentum of the connected operating parts, in which 50 event it will be returned to the normal stopping point by a spring (not shown) and stopped in the proper position by the engagement of its aforesaid stop-face with a stop-lever 63, this stop-lever having an ex- 55 tension 64 in contact with the under side of the lower arm of the elbow-lever 36, against which latter it is normally held by a spring (not shown) so as to be movable therewith. Hence when the slide-bar 39 60 is raised into operative position to effect the stopping of the machine, the stop-lever 63 rises with it into its operative position, and when the slide-bar is moved downward to permit the re-starting of the machine, it 65 positively carries the said stop-lever with it.

The stop-mechanism is intended to be controlled automatically, and I have shown herein a releasing-bar 70 pivoted to the lever-arm 27 and having a hooked rear end for engaging and releasing an elbow-lever 74 and also having a cam face for shifting the position of the hooked end of said bar. The hooked end of the bar 70 does not operate the lever 74 to automatically stop the machine until the bar 70 is pulled toward 75 the needle during the formation of the last of the determined number of stitches, when said arm 70 is shifted by the lever-arm 27 and the slide-latch 49 is released from the slide-bar 39, whereupon the sewing operation is automatically stopped by the parts 80 previously described.

In my improved machine the automatic stop mechanism is intended to control the throwing into action of a device for engaging with and detaining the last loop cast off by the shuttle in a determined number of stitches and for spreading said loop in a desired position to permit the cutting of one side thereof without cutting the other. This 85 device I term a loop-detainer or loop-detainer and spreader. Said device is normally held out of action and is only brought into operation just prior to the casting off of the last loop by the shuttle prior to the 90 automatic stopping of the machine. I employ in the present instance an oscillatory loop-detainer, designated generally by 75, which comprises a swinging arm of peculiar construction secured to the forward end of 95 a short rock-shaft 70 which is journaled in bearings below the main shaft 6 and having at its rear end another rock-arm 71 carrying an anti-friction roller 72, the latter being normally engaged by the cam arm 48 of the 100 rock-shaft 46 during the sewing operation of the machine and held thereby with the loop-detainer in an inoperative position relative to the shuttle, as shown in Fig. 9. The 105 operations of the parts are so timed that the loop-detainer is not released by the cam-arm 48 until the last loop of the series of stitches is cast off by the hook of the shuttle 5, and this movement of the arm 48 will take place just before the slide-bar 39 is released by 110 the slide-latch 49, as hereinbefore described. The loop detainer and spreader preferably has a hook 76 forming a recess 77 in which the needle-thread loop may be received, and 115 said detainer may also have a spreader, preferably in the form of a lateral wing or flange 78, for deflecting the two sides of the loop away from a common path and spreading them a considerable distance apart, the object of this being to enable the cutter here- 120 after described to cut one side of the loop thread without severing the other. The hooked portion of the loop detainer preferably forms a guide for the loop, as shown in Fig. 10, and it may be stopped in its 125 130

working position, when thrown into action by the spring 73, by a wall of the shuttle-race 80, or by any other suitable stop-face. When the detainer is stopped, as shown, the 5 loop cast off by the needle enters the recess 77 without meeting any obstruction and is detained by the end wall of said recess and is also spread by the lateral wing 78 as more clearly shown in Figs. 13 and 14. Owing 10 to the fact that this last loop of a series is detained and not drawn up into the work by the take-up, it is necessary to provide means for releasing the tension on the needle-thread by the time the loop reaches the 15 position shown in Fig. 10.

Any ordinary type of tension device, such as 85, which in this case comprises two plates or disks held together by spring pressure, may be employed for tensioning the thread, 20 and in connection therewith a tension-releasing device may be used which will operate immediately after the slack in the loop, shown in Fig. 10, is taken up by the take-up device 7. In order to accomplish this release of the tension the disks of the tension 25 device 85 are preferably spread apart by the wedge-shape end 86 of a long tension-releasing lever 87 pivoted on the side of the overhanging arm 2. This lever has at its 30 rear end a pivotal connection with a link 88, the lower end of which in turn is pivoted to a shiftable intermediate or plate 89, pivoted at 90 on a stud on the framework and having near its lower end a slot in which 35 works a pin 92, secured to the slide-bar 39 (see Figs. 1 and 6). At its upper end said plate has an anti-friction roll 93, which, when the pin 92 holds the plate in its lower-most position, is normally held out of the path of a cam 94 in fixed relation with the upper shaft 3. When the slide-bar 39 is released and rises, however, the pin 92 permits the roll 93 to be carried by a spring 94' 40 into operative relation with the circular face of the cam 94, and at the same time said pin permits the lever 87 and its wedge-shaped end 86 to move to the position shown in Fig. 1. The antifriction roll 93 prevents the separation of the disks of the tension device 45 until said roll is near the center of the flattened cam-face 94' of the cam 94, when the wedge 86 will be permitted to enter between and separate said disks long enough to permit the take-up device 7 to move upward a 50 considerable distance and pull off thread from the spool. Before the take-up reaches the limit of its upward movement, however, the roll 93 should ride away from the center of the flattened cam-face 94' to cause the 55 withdrawal of the wedge 86 and the re-tensioning of the needle thread, the movements of the parts being so timed and of such extent that after the re-tensioning of the 60 thread the take-up 7 will rise a short distance, usually to the limit of its upward 65

movement, and put the thread of the last loop cast off by the shuttle under its normal tension to hold such thread taut during the cutting thereof.

In all of the principal views the mechanism is shown with the parts in the positions they occupy immediately after the machine has been brought to a stop by the action of the stop mechanism. All of the parts are now in position to permit the cutting of the needle and bobbin threads and the release of the work from the button-holder. In the foregoing description I have set forth the manner in which the needle thread loop is held by the loop-detainer, and thus kept 70 from being drawn up into the work, whereby a considerable length of thread is provided to form a cut end, it being necessary that the length of the severed end of the needle thread below the eye of the needle 75 shall be sufficient to permit the formation of the stitch when the machine is started again automatically. It is also important to leave a sufficient length of thread at the cut end of the bobbin thread for the 80 same purpose. For this reason I make use of a suitable bobbin-thread deflector or detainer in the form of a pull-off which is coöperative with the needle-thread deflector, or combined detainer and spreader, said 85 pull-off for the bobbin-thread being preferably associated, and movable, directly with a thread-cutter, preferably so constructed as to be capable of severing both 90 the needle-thread and the bobbin-thread. 95 In this construction (see Figs. 11-14 inclusive) the bobbin-thread pull-off 100 is pivoted at a suitable fixed point 100^a on the under side of the throat-plate and at its 100 working end is so shaped as to form a 105 notch or recess 101, constituting the pull-off proper, the path of movement of this finger being such as to cause the walls of the recess 101 to engage the bobbin-thread 110 102 when a working stroke is imparted to such finger, and to carry such thread toward the rear of the machine and form a bight or loop by pulling off an additional quantity of thread from the bobbin, and thereby provide a sufficient amount of 115 thread to form an end of considerable length when such thread is cut.

Any suitable form of thread-cutting device may coöperate with the parts just described to sever the needle and bobbin 120 threads. In this case a movable shear or blade 105 is secured to the pull-off device 100 with the cutting edge thereof extending across, and immediately in advance of, the back wall of a slot in the pull-off finger, 125 which slot is indicated at 106, a coöperating fixed shear or knife-edge 106', which in this case is the edge of a plate 106'' secured to the under side of the throat-plate, being located in the path of the movable 130

shear 105, against which fixed shear edge the bobbin-thread 102 and one side 107 of the loop formed in the needle-thread may be cut. The two sides 107 and 108 of the loop are kept apart by the spreader 78, as shown in Fig. 13, and as the pull-off device 100 moves to the position shown in Figs. 12 and 14, it receives the bobbin-thread in the recess 101 and pulls off an extra quantity of thread from the bobbin. During this movement of the pull-off device 100 the side 107 of the loop in the needle-thread enters the slot 106, but the other side 108 of the loop is held clear of the inner edge 109 of the pull-off device 100 and does not enter the slot 106. The side 108 of the loop is therefore out of the path of the movable shear 105 and is not cut by it, and hence a long end depends through the opening in the throat-plate on the drawing up of the needle, this end being of sufficient length to permit the formation of a loop on the next descent of the needle, the loose end of said thread being preferably gripped and held automatically after the hook of the shuttle begins to pull out such loop in the usual manner.

The parts just described for cutting the threads may be operated in any suitable way, but I prefer to organize them in such a manner that they will coöperate with the presser-bar and presser-foot, which latter in this case is a part of the button-holder, this mode of organizing the parts being desirable in order that the operator may cut the threads and raise the button-holder from the work, into a position where the button may be disengaged from the holder and the work shifted, by a single operation. Here, the angular bobbin-thread pull-off has on its under side a pivoted squared guide 110, which works in the forked end of a rock-lever 112, pivoted on the under side of the bed-plate and operated by a long connecting-rod or pull-wire 113, the rear end of which is pivoted to the lower end of a long guide-arm 114, pivoted near the rear end of the forward side of the overhanging arm 2, a suitable spring 115 serving to return these parts to their normal positions with the cutter and the pull-off out of the path of the threads. Near its lower end a link 116 connects the long guide-arm 114 to a short rock-arm 117 fastened to the forward end of a rock-shaft 118 which passes through and is journaled in the head of the machine near the lower end thereof, and has at the rear side of the machine a rock-arm 119, carrying a spring-pressed by-pass pawl 120 having an oblique face in the path of an anti-friction roll 121 on the rod 30, by means of which latter the presser-bar may be raised on the depression of a treadle (not shown) by the operator. At its upper end the connecting-rod 30 has a slot 122 of considerable length, so as to pro-

vide for a certain lost motion to permit the thread-cutter and the pull-off to be operated before the presser-bar-lever 123 is operated to raise the presser-bar. In this case an independent spring 124 is employed for returning the connecting-rod 30 to its normal position, in addition to that which is shown at 125 for lowering the presser-bar and its lever.

After the threads have been cut and the work shifted to a new position the thread-cutter and pull-off may be returned to their normal positions and the presser-bar and button-holder lowered again into engagement with the work. Thereupon, the machine may be started again by turning the rock-shaft 46 by a suitable connection with the rock-arm 48, which will cause the elbow-lever 36 to be operated and the pulley 35 to be clutched to the pulley 34 again, and at the same time the slide-bar and the stop-lever will be withdrawn from engagement with the lips on the stop-rings, and the intermediate or plate 89 lowered to carry the anti-friction roll 93 away from the cam 94. This operation also resets the slide-latch and locks the same with its rear end in position to be operated again by the lever 74 at the proper time.

I have hereinbefore stated that the loose end of the cut needle-thread should be firmly gripped and held at the beginning of the operation of the machine, and as the pulleys 34 and 35 are now clutched again to start the machine the construction and operation of the gripping means shown herein will now be described. The switch-cam 24 hereinbefore referred to makes one complete rotation for each complete cycle of operations of the machine, and for this reason said cam also preferably has a peripheral cam face 130 controlling the operation of the gripping device. In this construction one arm of an angle-lever, which arm is designated by 131, has an anti-friction roll 132 in contact with the periphery of said switch-cam, and the other arm 133 of said angle-lever has a loose pin-and-slot connection (formed by a long slot 133' and a pin 134) with a slide 135 operating in a suitable way in the bed-plate and having at its forward end a gripping finger 136 adapted to catch the rear side of the loop thrown out by the needle, as shown in Fig. 15, and grip the same between it and the under side of the edge of the opening 137 in the throat-plate through which the needle passes, as shown in Fig. 16, the gripping finger preferably advancing and withdrawing a short distance to alternately grip and release the thread at each turn of the shaft 6. The reason for this is that at the beginning of the sewing operation the anti-friction roll 132 rides down the cam-face 130 and permits the slide 135, which is normally in an inoperative position, to be shifted

ed to an operative position, said slide having in this case a stud 140 depending therefrom and carrying an anti-friction roll 141 normally out of the path of a circular face-cam 5 142 on the shaft 6, this roll being shifted, however, into engagement with said face by means of a suitable spring, such as 143, and held against said face 142 at all points in the circuit thereof. Hence, the roll 141 and the 10 gripping finger 136 connected therewith are reciprocated back and forth at each stitch-forming operation during the formation of the first few stitches, and this action continues until the switch-cam 24 turns far 15 enough to cause the roller 132 and its angle-lever to be shifted again to withdraw the roll 141 away from the cam-face 142 to its inoperative position. As an important feature in the operation of this thread-gripping 20 device, the latter is so controlled by the peripheral cam-face of the switch-cam 24 as not to come into operation until the second descent of the needle. This permits the loose end of the thread to be carried below the 25 work upon the first descent of the needle and, as the thread is gripped by the gripping finger 136 upon the second descent of the needle, such loose end of the thread will be thereby prevented from being again 30 drawn or pulled upward through the work. In this way the loose end of the thread will always be located on the under side of the work.

What I claim is:—

- 35 1. In a sewing machine, the combination with stitch-forming mechanism embodying a needle and a bobbin, of an automatic stop-mechanism, a detainer for the needle thread operative to engage the thread beneath the 40 work plate, controlling connections between said needle thread detainer and said stop mechanism, an independently controlled detainer for the bobbin thread, and a thread cutter coöperative with said detainers.
- 45 2. In a sewing machine, the combination with stitch-forming mechanism embodying a needle and a bobbin, of an automatic stop mechanism, two independently acting thread 50 detainers for controlling the needle and bobbin threads respectively, the needle thread detainer being operative to engage the thread beneath the work-plate and being controlled by said stop mechanism, and the bobbin thread detainer being operative subsequent to the stopping of the machine and being manually controlled, and a thread cutter coöperative with said detainers.
- 55 3. In a sewing machine, the combination with stitch-forming mechanism embodying a needle and a bobbin, of an automatic stop mechanism, a needle thread deflector engaging the thread beneath the work plate, controlling connections between said deflector and said stop mechanism, an independently 60 controlled deflector for the bobbin thread,

and a thread cutter coöperative with said defectors.

4. In a sewing machine, the combination with stitch-forming mechanism embodying a needle and a bobbin, of an automatic stop mechanism, two independently acting thread deflectors for controlling the needle and bobbin threads respectively, the needle thread deflector being operative to engage the thread beneath the work-plate and being controlled by said stop-mechanism, and the bobbin thread deflector being operative subsequent to the stopping of the machine and being manually controlled, and a thread cutter coöperative with said deflectors.

5. In a sewing machine, the combination with stitch-forming mechanism embodying a needle and a bobbin, of two independently acting normally inoperative thread detainers for controlling the needle and bobbin thread respectively, the needle thread detainer being operative prior to the stopping of the machine and the bobbin thread detainer being operative subsequent to the stopping of the machine, an automatic detainer-controlling stop mechanism for throwing the needle thread detainer into action, and a thread cutter coöperative with said detainers.

6. In a sewing machine, the combination with stitch-forming mechanism embodying a needle and a bobbin, of an automatic stop mechanism, a combined loop detainer and spreader and a bobbin thread detainer controlling the needle and bobbin threads respectively, one of said detainers being controlled by said stop mechanism independent of the other, and a thread cutter coöperative with said loop detainer and spreader and said bobbin thread detainer.

7. In a sewing machine, the combination with stitch-forming mechanism, of an automatic stop-mechanism, a normally inoperative loop-detainer and spreader controlled by said stop mechanism and automatically thrown into action thereby upon the stopping of the machine, and a manually-controlled thread-cutter movable in the path of one side only of the loop and being operative subsequent to the stopping of the machine.

8. In a sewing machine, the combination with stitch-forming mechanism, of an automatic stop-mechanism, a normally inoperative loop-detainer and spreader for deflecting one side of the loop away from the cutter and being controlled by said stop mechanism, and a thread-cutter movable in the path of one side only of said loop and being supported and operative independent of the loop-detainer and spreader.

9. In a sewing machine, the combination with stitch-forming mechanism, of a take-up device for the needle-thread, a thread cutter, a loop detainer, means for throwing

said loop detainer into action, a tension device and a tension-releasing device organized and timed to release the thread after the throwing of the loop-detainer into action and to retension the same prior to the completion of the take-up action.

10. In a sewing-machine, the combination with stitch-forming mechanism, of a take-up device for the needle-thread, a thread cutter, a normally inoperative thread-detainer, an automatic stop-mechanism for throwing said detainer into action, a tension device, and a tension-releasing device organized and timed to release the thread after the throwing of the detainer into action and to retension the same prior to the completion of the take-up action.

11. In a sewing machine, the combination with stitch-forming mechanism, of a normally inoperative loop-detainer, an automatic mechanism for throwing said detainer into action, a thread cutter, a tension device, and a tension-releasing device organized and timed to release the thread momentarily subsequent to the throwing of the detainer into action and thereafter retension the thread prior to the operation of the cutter.

12. In a sewing machine, the combination with stitch-forming mechanism embodying a needle and a looper, of a take-up device for the needle thread, a normally inoperative loop detainer, an automatic stop mechanism for throwing said loop detainer into action, a tension releasing device organized and timed to release and retension the loop during the take-up movement after the throwing of the detainer into action, and a thread cutter coöoperative with said loop detainer.

13. In a sewing machine, the combination with stitch-forming mechanism embodying a needle and a looper, of a take-up device, a normally inoperative loop detainer, an automatic stop mechanism for throwing said loop detainer into action, a tension-releasing device organized and timed to release the loop momentarily during part of the take-up movement after the throwing of the detainer into action and to retension said thread before the end of said take-up movement, and a thread cutter coöoperative with said loop detainer.

14. In a sewing machine, in combination, stitch-forming mechanism, a thread gripper, means for reciprocating said gripper in unison with the stitch-forming mechanism, means for rendering said gripper active after the first reciprocation of the needle at the restarting of the stitch-forming mechanism, whereby the loose end of the needle thread is located at the underside of the work, and mechanism for rendering the thread gripper inactive.

15. In a sewing machine, the combination with stitch-forming mechanism embodying a needle and a bobbin, of an automatic stop

mechanism, a loop detainer and spreader for engaging the needle thread, a bobbin-thread pull-off, and a thread-cutter operative in the path of the bobbin-thread and in the path of one side only of the loop in the needle-thread.

16. In a sewing machine, the combination with stitch-forming mechanism embodying a needle and a bobbin, of a loop-detainer and spreader for engaging the needle-thread, a bobbin-thread pull-off having means for engaging one side of the loop held by said detainer and spreader, and a thread-cutter operative in the path of the thread engaged by said pull-off.

17. In a sewing machine, the combination with stitch-forming mechanism embodying a needle and a bobbin, of a loop detainer and spreader for engaging the needle-thread, a bobbin-thread pull-off having a slot for receiving one side of the loop held by said detainer and spreader, and a thread-cutter operative in the path of the threads engaged by said pull-off.

18. In a sewing machine, the combination with a thread-cutting device located beneath the work-plate of the machine and adjacent to the point of descent of the needle, of a thread-gripping device comprising a plate bearing against the underside of said work plate, and operating means whereby the said thread-gripping plate is caused to engage said needle thread and grip the same beneath the work-plate during the formation of the first stitch made subsequent to the thread-severing operation.

19. In a sewing machine, the combination with a thread-cutting device located beneath the work plate of the machine and adjacent to the point of descent of the needle, of a stop-motion device whereby groups of a predetermined number of stitches may be formed, a thread-gripping plate arranged to press the thread against the underside of said work plate, and operating means whereby said thread-gripping plate is caused to engage the severed end of the needle thread and grip the same beneath the work-plate during the formation of the first stitch of a group, and prevent it from being drawn up through the needle hole of the work-plate.

20. In a sewing machine, the combination with stitch-forming mechanism including a reciprocating needle carrying an upper thread and a coöperating loop-taker, of a thread severing device independent of the stitch-forming mechanism and comprising an implement for entering and positioning a loop of upper thread, a movable implement for severing one limb of said thread-loop, and independently acting means whereby said implements are differentially actuated.

21. In a sewing machine, the combination with stitch-forming mechanism embodying a needle and a bobbin, of an automatic stop

mechanism, a detainer and spreader for the
needle thread, an independent detainer for
the bobbin thread, controlling connections
between one of said detainers and said stop
5 mechanism, and a thread cutter coöperative
with said detainers.

In testimony whereof, I have signed my

name to this specification in the presence of
two subscribing witnesses, this fifth day of
May 1902.

DANIEL MILLS.
